UNITED STATES PATENT OFFICE.

GRANT B. SHIPLEY, OF MILWAUKEE, WISCONSIN.

APPARATUS FOR PRESERVING WOOD.

1,081,158.

Specification of Letters Patent.

Patented Dec. 9, 1913.

Application filed July 31, 1911. Serial No. 641,463.

To all whom it may concern:

Be it known that I, GRANT B. SHIPLEY, a citizen of the United States, and resident of Milwaukee, in the county of Milwaukee and State of Wisconsin, have invented a new and useful Improvement in Apparatus for Preserving Wood; and I do hereby declare the following to be a full, clear, and exact description thereof.

10 My invention relates to the preserving or creosoting of wood, such as wooden railroad ties. Its object is to provide suitable apparatus by which the amount of preservative or creosoting fluid injected into and remaining in the wood can be more accurately and readily measured than heretofore, and at less expense, and in general to improve on the practice previously followed in the art.

Various processes have been employed in the past in preserving wood by forcing the desired quantity of antiseptic, such as coal tar creosote, zinc chlorid, or other fungus destroying material into the wood, usually ties or timber; the main object of such processes being to thoroughly impregnate the cells of the wood with the antiseptic fluid without leaving too great an excess of fluid within the cells, the latter contingency causing obviously added expense without appreciably increasing the efficiency of the result. Thus in one well known method, the wood is incased in a treating cylinder, which is then sealed and within which the air pressure is raised to from 40 to 80 pounds per square inch or more or less as required. Without releasing this pressure, the creosote or preserving fluid is allowed to flow from a separate pressure tank or reservoir, at the same interior air pressure, into the treating cylinder by gravity, and hence into the wood under the air pressure, the air being displaced and returned to the reservoir or pressure tank. Further creosote is then forced into the wood by a pressure pump which receives its supply from a separate open measuring tank. When the desired quantity of preservative, as indicated by the measuring tank, is forced into the wood in accordance with this method, the pressure pump is then stopped and the creosote either pumped or blown back by air to the reservoir or drained into the underground tank. The treating cylinder is then closed and the surplus creosote drained by suction from the wood.

55 After the vacuum is completed, the valves on the treating cylinder are again opened

and the creosote either pumped or blown back by air to the reservoir or drained into the underground tank, the treated wood being then ready for use. This practice, as well as all others, so far as I am informed, depends on the volume measurement of the creosote which is forced into the wood for estimating the amount of the same so employed, and hence the extent of the process. As a difference of $22\frac{1}{2}$ F. in temperature means in general a difference of 1 per cent. in volume, and hence substantially inversely in weight of coal tar creosote, and as differences of 65° to 100° between the temperature of the creosote in the open measuring tanks and that in the treating cylinder and in the pressure tank are usually present, it is apparent that the amount of preservative forced into the wood cannot be accurately measured by any of the processes in which it is volumetrically measured in an open tank.

In the preferred practice of my invention I therefore employ a tank or reservoir in which the preserving fluid is carried under the desired air pressure, the said tank being coupled or joined by flexible connections to the treating cylinder or retort and to the storage tank or source of preserving fluid, and mounted on weighing apparatus or scales so that the amount of creosote or other preserving fluid in it can be accurately weighed at any stage of the operation. As I believe the employment of such means to be essential to the practice of such improved process the same is claimed herein.

In the accompanying drawings Figure 1 is a side view of my improved apparatus. Fig. 2 is a plan view of the same. Fig. 3 is a detail end view on a larger scale showing a tank platform and scales illustrated in Fig. 1. Fig. 4 is a detail vertical section on an enlarged scale of the top or dome of one of the pressure tanks.

In the said drawings, the fluid preservatives, such as liquid coal tar creosote is stored in the storage tank 1 from which leads the supply pipe 2 having the valve 2' and connecting with the header 3. The general service pump 4 is connected with said header 3 by pipes 5, and is arranged to pump fluid through the storage tank supply pipes 6, 7, provided with the valves 6', 7', respectively, to the reservoirs or pressure working tanks 22 and 23.

The pipes 6 and 7 respectively are shown

as connected to the reservoir pipes 16 and 17 respectively, the said reservoir pipes being provided with the valves 16' and 17', respectively. These reservoir pipes 16, 17 have suitable elbow portions 18 and 19, respectively, which are provided with the flexible couplings 20, 21, respectively. These couplings 20, 21 are suitable metallic universal couplings of any desired type, that known as 10 the Moran joint being entirely adequate for the purpose.

The portions 18', 19' respectively of the elbow pipes 18 and 19 are rigidly attached to the working tanks 22 and 23, respectively. 15 These reservoirs are in all respects similar, two being employed merely for purposes of convenience; and each is provided at its upper end with a hood 24 communicating with a pipe connection 25 as illustrated in 20 Figs. 2 and 4. The pipe connection 25 is provided with the valve seat 26 against which seats the ball float valve 27, including the ball float 28, the valve stem 29, the spring 30, lever 31, and weight 32. As the 25 valve 27 is upwardly closing under the influence of the ball 28, spring 30 and weight 32, the spring being adjustable by the spring cap nut 30', the valve 27 acts to close or seal the particular tank 22 or 23 to which 30 it is applied against the entrance of compressed air through the pipes 34 or 35, respectively. The pipes 34 and 35 are provided respectively with the flexible couplings 36 and 37 similar to the coupling 35 joints 20, 21, above referred to, and are connected by the elbows 34' and 35' to the vertical pipes 38 and 39, respectively, having horizontal portions 38' and 39' connected to the header pipe 40. The pipe 40 40 communicates with the vacuum pumps 41 and also with the pipe 54 leading from the air receiver 50, connected by the pipe 52 to the compressor pump 51. The pipe 40 also communicates by its elbow portion 40' 45 with the treating cylinder or retort 42. This cylinder or retort 42 is arranged preferably in horizontal position and is connected directly to the vertically arranged pressure working tanks 22 and 23 through the tank 50 pipes 16 and 17 respectively, by the connecting pipes 43 and 44, respectively. The pipes 43 and 44 are provided with the valves 43', 44' having the elongated stems 43^a, 43^b by which they can be conveniently controlled by the 55 operator working the hand wheels 43^c and 43^d, respectively. The treating cylinder 42 is also connected to the source of preserving fluid or pipe 6 leading therefrom through the pipe 46, pump 47 and pipe 48 provided 60 with a valve 48'. As illustrated the pump 47 is likewise connected to the pipe 7 leading from the source of preserving fluid by the pipe 49 provided with the valve 49'. The valves 48' and 49' are provided with 65 the depending valve stems 48^a and 48^b hav-

ing the hand wheels 48^c and 48^d so as to be conveniently accessible to an operator standing in convenient position below the tanks 22 and 23 to operate the valves 43' and 44' referred to above.

Compressed air is conveniently supplied to the pressure working tanks 22, 23 and to the treating reservoir 42 from the receiver 50 in which it is stored by the air compressor pump 51 communicating therewith through the pipe 52. The pipe 53 leads directly from the receiver 50 and communicates with the connecting pipe 54 which joins the header pipe 40. The pipe connections 34, 38, 38', and 35, 39, and 39', respectively also connect with the header pipe 40, the pipes 38' and 39' being provided respectively with the valves 38^a and 39^a. The pipe 40 is provided also with the valve 40^a, so that when this valve is closed, and the valves 38^a and 39^a are open, compressed air may be directed from the reservoir 50 through the pipes 53, 54, 40 and 38', 39', etc., into the reservoirs 22 and 23.

The treating cylinder or retort 42 is provided with a dome or hood 56 having the valve 57 provided with the weighted arm 58 and similar also in other respects to the valves 27 carried in the domes 24 of the reservoirs 22 and 23, respectively. The valve 57, which is downwardly opening acts in conjunction with the valves 27 to equalize the pressure of air in the reservoirs 22, 23 and treating cylinder or retort 42; so that when the valve 40^a is opened as well as the valves 38^a and 39^a compressed air will enter all three cylinders from the receiver 50 or air compressor 51 and produce an equal pressure therein, for the purpose described more fully below. The treating cylinder 42 100 is provided with a removable end door 60, which may be sealed when it is desired to close the cylinder and opened when it is desired to remove or insert wood or timber therein. The trackway 61 extends also preferably within the cylinder 42, as indicated in Fig. 1. The storage reservoirs or pressure tanks 22 and 23 are carried, in accordance with my invention, on the scale pans 65, 66, respectively, which are formed conveniently of I-beams 65' and 66' resting on the transverse beams 65'' and 66''. The scale pans 65 and 66 are each supported on suitable platforms and levers, those supporting the pans 65 being illustrated diagrammatically at 71 in Fig. 3. The scale pan 65 is also connected by the rod 72 to the arm 73 of the weighing device 74; and the scale pan 66 is connected by a similar rod 75 to the arm 76 of the weighing device 77. The weighing devices 74 and 77 are provided with suitable means such as scale beams 74' or 77' for accurately measuring the weight of the tanks or reservoirs 22 and 23, respectively, with their contents. As the weight 110

of such tanks is known or can be ascertained in each instance, I thus provide simple means for accurately weighing the preserving fluid in each pressure tank at any stage of the operation. The treating cylinder 42 is also connected by the return pipe 80 controlled by the valve 80' to the storage tank 1 through the elbow valve 2^b of the pipe 2, as illustrated, for the purpose of returning 10 the preservative fluid directly to such tank 1 in an alternative practice of my invention, as described below.

In the use of my invention, assuming that the treating retort 42 is entirely empty, the 15 timber is first filled into the same, preferably a suitable car on the trackway 61 being utilized, and the treating cylinder 42 then sealed by the cap 60. The creosoting or preserving fluid is then or previously pumped 20 by the general service pump 34 from the storage tank 1 through the pipes 6 and 7 into the tanks 22 and 23, respectively. In this operation the valves 6' and 7' are opened in the apparatus just described, and 25 the fluid, in reaching the tank 22 for instance, passes through the pipe 6 and tank pipe 16 passing the valve 16', which is also open and through the elbow pipe 18, including the flexible connection 20 to the tank 30 22, the valves 43' and 48' being closed during this step. This pumping operation is continued until the desired weight of fluid, as indicated by the weighing devices 74 and 77 is obtained in each tank 22, 23. The 35 desired uniform pressure of say 40 to 80 pounds per square inch is then produced within both the tanks 22, 23, and the treating cylinder 42 by allowing air to pass from the receiver 50 to both the tanks and the 40 treating cylinder. As indicated above in the apparatus shown this is accomplished by closing the valves 43' and 44', and opening the valves 54^a in the pipe 54 and the valves 40^a, 39^a and 38^a in the pipes 40, 39' and 38' 45 respectively. The valves 43', 44' may then be opened, the valves 6', 7' being closed, and the preserving liquid allowed to run down by gravity into the treating cylinder 42. Thus in its course from the tank 22 the 50 liquid passes through the elbow pipe 18, including the flexible joint 20, the pipe 16, including the valve 16', and the pipe 43 into the treating cylinder 42. As the pressure is substantially the same in the tank 55 and the treating cylinder 42 due to the previous operation of introducing air into each of them from the receiver 50 and past the controlling valves 27, 27 and 57, respectively, it is apparent that the preserving 60 liquid will flow freely downwardly into the retort 42 until it is full, closing the float valve 57 (similar to valve 27) in the dome 56 when it has filled the cylinder 42 and being forced into the wood by whatever air 65 pressure is present in the tank, say 40 to 80

pounds to the square inch. A considerable quantity of fluid is thus injected into the wood, the amount thereof being preferably ascertained as described below.

As the tanks 22 and 23 are flexibly connected to the pipes 16, 38 and 17, 39 by the flexible couplings 20 and 36 and 21 and 37 in the elbow pipes 18' and 34 and 19' and 35, respectively, the scale beams 74' and 77', respectively indicate the weight of fluid in the 75 tanks 22 and 23 at any desired stage of the operation. In general, however, the fluid remaining in each tank as 22, 23, is carefully weighed after its free flow under constant pressure in each tank 22, 23 has ceased. The 80 amount of fluid which has passed into the treating cylinder 42 under constant pressure is thereby indicated. The desired amount of additional preserving fluid is then forced into the treating retort 42 and wood within 85 the same by means of the fluid pressure pump 47. The valves 48' and 49' in the pipes 48, 49 leading to this pump 47 from the pipes 43 and 44 respectively, are then 90 opened by turning the hand wheels 48^a and 48^b, respectively, the valves 43' and 44' having been closed as by turning the hand wheels 43^a and 43^b, respectively. The pump 47 being then set in action, the preserving liquid is sucked through the pipes 48 and 49 95 and forced by the pump through the pipe 46 into the retort 42. This results in forcing the liquid at high pressure into the wood within the retort 42, and the operation is carried on until the required weight of such 100 liquid as measured by the scales 74 and 77, has been forced into the wood. The operation of the pump 47 is then stopped.

The succeeding steps may be carried on according to the particular mode of treatment 105 followed, one form consisting in draining the fluid in the retort 42 back into the storage tank 1 by opening the valves 80' in the pipe 80 in the apparatus shown and closing the valve 48' and 49' in the pipes 48 and 49. 110 The pressure of the air remaining in the cylinder 42 aids in this step by expelling the fluid; and the service pump 4 (shown diagrammatically as connected to the return pipe 80) being in general subsequently employed in reversed operation to suck or draw remaining excess fluid from the wood in the cylinder 42 through the pipe 80 back to the storage tank. If desired, however, especially where it is required to ascertain 115 the amount of fluid remaining in the wood with the greatest accuracy, the pump 47 may simply be reversed, the valves 6' and 7' remaining closed, and the valves 48' and 49' remaining open; and the fluid pumped 120 out of the retort 42 and back through the pipes 48 and 49 and 16 and 17 into the tanks 22 and 23. This operation is continued until the treating retort 42 is entirely empty of preserving fluid or creosote; and the amount 125 130

of fluid returned to the tanks 22 and 23 measured by weighing the same. The operation of the pump 47 may then be continued, and excess fluid in the wood sucked out 5 therefrom and returned to the tanks 22 and 23, wherein it is accurately weighed. The required amount of preservative actually forced into and remaining in the wood is therefore readily ascertained. The door cap 10 60 is then opened and the treated wood removed therefrom. Thereafter the cycle of operations may be repeated in the above manner or as suitably modified when so desired. In fact it will be understood that my 15 invention includes broadly the weighing of the preserving fluid as distinguished from measuring the same volumetrically, and more specifically the weighing of the fluid in the same tank as that from which it has 20 been fed by gravity to the wood being treated in accordance with the preferred method described above. As the price of the finished product depends in each case essentially upon the amount of preserving material injected into the same, by ascertaining 25 the exact weight of preservative so employed, influenced by variations in temperature in different parts of the apparatus, I thus increase the commercial efficiency of the 30 operation.

What I claim is:

1. In apparatus for preserving wood, the combination with a retort for wood, a source of preservative fluid, a measuring tank, means for conveying fluid from said source to said tank, means for weighing the contents of said tank, means for producing uniform pressures in said tank and retort in excess of atmospheric pressure, means for conducting preserving fluid after weighing the same in said tank to said retort, and separate pressure means for conveying additional fluid to said retort under pressure in excess of that existing in said retort. 40
2. In apparatus for preserving wood, the combination with a retort for wood, a source of preservative fluid, a measuring tank, means for conveying fluid from said source to said tank, means for weighing the contents 45 of said tank, means for producing uniform pressures in said tank and retort in excess of atmospheric pressure, means for conducting preserving fluid after weighing the same in said tank to said retort, and means for conveying additional fluid to said retort under pressure in excess of that existing in said retort, and means for returning excess fluid from said retort to said source. 50
3. In apparatus for preserving wood, the combination with a retort for wood, a source of preservative fluid, a measuring tank, means for conveying fluid from said source to said tank, means for weighing the contents of said tank, means for producing uniform 55 pressure in said tank and retort in excess of atmospheric pressure, the 60 combination with a retort for wood, a source of preservative fluid, a measuring tank, means for conveying fluid from said source to said tank, means for weighing the contents of said tank, means for producing uniform pressure in said tank and retort in excess of atmospheric pressure, the 65 combination with a retort for wood, a source of preservative fluid, a measuring tank, means for conveying fluid from said source to said tank, means for weighing the contents of said tank, means for producing uniform pressure in said tank and retort in

excess of atmospheric pressure, means for conducting preserving fluid after weighing the same in said tank to said retort, and means for conveying additional fluid to said retort under pressure in excess of that existing in said retort, and means for returning excess fluid from said retort to said measuring tank for reweighing. 70

4. In apparatus for preserving wood, the combination with a retort for wood, a source of preservative fluid, a measuring tank, means for conveying fluid from said source to said tank, means for weighing the contents of said tank, means for producing uniform pressures in said tank and retort in 80 excess of atmospheric pressure, means for conducting preserving fluid after weighing the same in said tank to said retort, and means for conveying additional fluid to said retort under pressure in excess of that existing in said retort, and means for returning excess fluid from said retort to said measuring tank for reweighing, and means for returning the reweighed fluid to said source. 85

5. In apparatus for preserving wood, the combination of a retort for wood and a source of preserving fluid, a measuring tank for said fluid, a source of pressure for conveying fluid from its source to said tank, 90 a weighing scale supporting said tank whereby the varying weights of fluid within said tank may be determined, a second source of pressure for producing uniform pressures in said tank and retort in excess 100 of atmospheric pressure, means for conveying fluid from said tank to said retort under said uniform pressures, and means for conveying additional quantities of said fluid from said tank to said retort at a pressure in excess of said uniform pressure. 105

6. In apparatus for preserving wood, the combination of the retort for wood and a source of preserving fluid, a measuring tank for said fluid, a source of pressure for conveying fluid from its source to said tank, a weighing scale supporting said tank whereby the varying weights of fluid within said tank may be determined, a second source of pressure for producing uniform pressures 110 in said tank and retort in excess of atmospheric pressure, means for conveying fluid from said tank to said retort under said uniform pressures, and means for conveying additional quantities of said fluid from said tank to said retort at a pressure in excess of said uniform pressure, and means for returning excess fluid from said retort to said tank for reweighing. 115

7. In apparatus for preserving wood, the 120 combination of a retort for wood, and a source of preserving fluid, a measuring tank for said fluid, a source of pressure for conveying fluid from its source to said tank, a weighing scale supporting said tank where- 125

by the varying weights of fluid within said tank may be determined, a second source of pressure for producing uniform pressures in said tank and retort in excess of atmospheric pressure, means for conveying fluid from said tank to said retort under said uniform pressures, and means for conveying additional quantities of said fluid from said tank to said retort at a pressure in excess of said uniform pressure, and means for re-

turning excess fluid from said retort to said tank for reweighing, and means for returning the fluid in said tank to said source of fluid.

In testimony whereof, I the said GRANT 15 B. SHIPLEY have hereunto set my hand.

GRANT B. SHIPLEY.
